INVENTOR

F. Alexander Purdy

UNITED STATES PATENT OFFICE.

FRED ALEXANDER PURDY, OF VANCOUVER, BRITISH COLUMBIA, CANADA.

RAILWAY-TICKET AND FORM THEREFOR.

1,312,205.

Specification of Letters Patent.

Patented Aug. 5, 1919.

Application filed October 14, 1915. Serial No. 55,817.

To all whom it may concern:

Be it known that I, FRED ALEXANDER PURDY, a citizen of the Dominion of Canada, residing at Vancouver, in the county of New 5 Westminster and Province of British Columbia, Canada, have invented new and useful Improvements in Railway-Tickets and Forms Therefor, of which the following is a specification.

10 This invention relates to railway tickets and forms therefor.

At the present time, as is well known to persons familiar with railway passenger traffic, almost an unlimited number of different tickets and ticket forms are required and used in connection with the different kinds of service rendered to passengers, each different service necessitating a new or different kind of ticket or ticket form. Thus, 20 there are different forms of tickets or different ticket forms for use between different stations on the road by which the tickets are issued and on all connecting roads and lines of transportation; also different forms for 25 one way, round trip and tour tickets; for the classes of service, as first class, second class, etc.; for parlor car, sleeping car, and other special service; the primary consideration being to serve passengers expeditiously at 30 the points of issue or sale.

Any saving in time effected in this respect, however, is offset many times by the time and study required by the railroad employees in familiarizing themselves with the 35 many different kinds of tickets and ticket forms used, whereby any desired ticket or ticket form may be selected quickly and accurately, and also by the work and attention required to keep an adequate supply of 40 all of the different kinds of tickets or ticket forms in stock, to say nothing of the large expense of printing relatively small quantities of many different kinds of tickets or ticket forms.

45 At the present time, also, the universal practice, so far as I am aware, is to number all tickets of the same kind consecutively, each coupon of tickets consisting of more than one coupon bearing the same number. 50 This is objectionable as no means are afforded whereby conductors and others are able to determine whether there was any irregularity in the issuing of the ticket, as by the unauthorized insertion or removal of 55 coupons, or otherwise, or by errors in issuance.

Heretofore, also, the agents' records of tickets issued, if any, have consisted either of a detachable stub on the ticket proper printed to partially or wholly correspond with the ticket proper and adapted to receive 60 entries of such items and matters relating to the ticket sold as it is desired to keep of record for the purpose of identifying the tickets sold or issued, or, where the tickets have no 65 stubs or equivalent parts, the records of tickets issued, if any, have consisted of written entries in books or upon sheets kept for the purpose. Both of these systems of keeping records of tickets issued are objectionable, the first because of possible omissions or errors in making the entries on the stubs, and the second because of the liability to omission and errors and also because of the 70 large amount of time, work and expense required for making the necessary entries.

The object of the present invention is to overcome all of the foregoing objectionable features, which end I attain by means of what may appropriately be designated a universal form of ticket for railway and other use, comprising a top or overlying strip of paper or the like, designed and adapted to receive original entries, and an underlying strip or strips adapted to receive carbon impressions of the original entries made on said top strip, and interposed carbon or transfer paper, said top strip consisting of an indefinite number of coupons detachably connected in series to form a strip of any 80 desired length, said coupons being of the same size and all containing facsimile printed matter and being provided with corresponding blank spaces adapted to receive appropriate entries, transfer impressions of 85 which are reproduced on said underlying strip or strips. Said coupons are detachable singly or in series to form the ticket proper and the registering lengths of said underlying strip or strips, containing carbon copies 90 of the entries made on said detached coupons, are detached therewith and form auditing and accounting records of tickets issued, said coupons being all numbered in consecutive series whether the ticket issued 95 comprises a single coupon or a plurality of coupons. My invention also comprises the various features and details of construction hereinafter described and claimed.

In the accompanying drawing, in which 110 my invention is fully illustrated, Figure 1 is a perspective view showing a

packet of ticket forms and underlying record strips of my invention, assembled for use.

Fig. 2 is a face or front view of a number 5 of ticket coupons of my invention filled in and detached to form tickets as issued to passengers; and

Figs. 3, 4 and 5 are isometric views of different forms of record sheets designed for 10 use in connection with my improved ticket forms.

Referring now particularly to Fig. 1 of the drawings, A designates, as a whole, a packet of ticket forms of my invention, comprising 15 a top strip *a*, underlying strips *a*¹, *a*² and *a*³ and carbon sheets *a*⁴, *a*⁵ and *a*⁶ interposed between the strips *a*, *a*¹, *a*² and *a*³. As shown, the strip *a*⁴ is double-faced and the strips *a*⁵ and *a*⁶ are formed by supplying a carbon 20 coating to the rear sides of the strips *a*¹ and *a*², whereby straight up carbon copies of original entries on the top strip *a* will be produced on the underlying strips *a*¹, *a*² and *a*³ and a reversed carbon copy of said entries 25 will be produced on the rear side of the strip *a*.

The top strip *a* consists of a series of coupons 1 all of which are of the same size and contain facsimile printed blank ticket forms 30 and which are provided with corresponding blank spaces adapted to receive appropriate entries to designate the destination of the passenger, the route and the class of service, and to identify the ticket, the date of sale, 35 and, if desired, the passenger in a general way, and such other data as may be desired. The printed blank ticket forms on said coupons 1 may and probably will vary according to the ideas of the person who prepares 40 the same. As the specific character of the entries and the arrangement thereof form no part of my present invention, it is not, therefore, considered necessary to describe in detail any particular character or arrangement 45 of such printed matter or blank spaces.

In Fig. 2 of the drawings, I have, for purposes of illustration, and to show the wide adaptability and range of use of my invention, shown a number of ticket coupons of 50 my invention filled in and detached to form tickets as issued to passengers. As in the form of coupon shown in Fig. 1, the character of the entries shown in Fig. 2 is illustrative merely and will be readily understood from an inspection of said figure without a description in detail of the entire appearing on the tickets therein shown.

Each packet of tickets may comprise an 60 indefinite and relatively large number of coupons, which are detachable from each other singly or any desired number at a time, to form the ticket proper which is delivered to the passenger, and the registering 65 lengths of the underlying strips *a*¹, *a*² and *a*³,

containing carbon copies of the entries on said detached coupons, are detached therewith and are designed to form the agent's record of tickets sold, and for auditing and accounting records of all tickets issued.

In tickets comprising a plurality of coupons, it has been customary to print at the head of the ticket a statement of the conditions on which the ticket is sold and defining the rights and liabilities of the issuing company and of the passengers incident to the passage or service called for by said ticket. Under this arrangement, it has been necessary to print the coupons in reversed order, that is, the coupons of said ticket are printed 70 to form a series extending from the bottom of the ticket upwardly in the order in which they are to be detached, the coupon to be detached first being arranged at the bottom of the ticket. In accordance with my invention, I contemplate printing the contract 75 between the company and the passenger on the back of the ticket, thus rendering it possible to number the coupons in the natural or regular order or sequence extending from 80 the top of the ticket downward.

Also, in accordance with my present invention, the ticket coupons are numbered 85 consecutively regardless of whether they are detached singly or whether a number of such 90 coupons are detached together, to form a single ticket. As previously stated, this prevents the possibility of errors and irregularity in the issuing of the tickets, as by 95 abstracting or inserting coupons—as the carbon copies forming the record of tickets sold 100 would at once disclose the absence or insertion of any coupons. The blank ticket forms can be thus numbered at the time they are 105 printed, but to insure that the tickets are numbered correctly, they will preferably be numbered by hand at the time they are issued.

Numbering the tickets in consecutive series from the top of the ticket downward 110 possesses an advantage and also effects an economy of time and study in issuing tickets by the ticket clerk. Heretofore in filling out a ticket comprising a plurality of coupons 115 and providing for different kinds of service, as transportation between a number of different points, it has been necessary for the ticket clerk before beginning to fill in the ticket, to figure out the number of coupons required and count down from the contract 120 for that number. If he made an error in his calculation, it was necessary for him, on discovering his error, to tear the ticket apart, insert or detach a coupon or coupons, and paste it together again. With my improved ticket form, however, it is possible 125 for the ticket clerk to begin with the coupon which is to form the ticket to be used first and to continue with the other coupons necessary to define the trip which the pas- 130

senger is to take, arranged in the order in which they are to be detached, no time or study being called for in his calculations as to the number and arrangement of the ticket 5 coupons.

In order to fix responsibility for errors which may occur in connection with filling out and issuing tickets, my invention also 10 contemplates applying to each coupon of each ticket issued a character—as a number—to identify the agent who issues the ticket. This will also preferably be done by hand at the time the ticket is issued.

As regards the strips a^1 , a^2 and a^3 which 15 form the record portions of the ticket, it is not necessary to print these as, due to the fact that the ticket coupons are all facsimiles of each other, the nature of the printing on the top strip a is well known to all persons 20 who have to do with the issuing of tickets. This is of advantage for the reason that it avoids the necessity of arranging the underlying strips a^1 , a^2 and a^3 in register with the printing on the top strip a , as would be 25 necessary if the printed matter on said top strip a were reproduced on the underlying strips.

The underlying strips a^1 , a^2 and a^3 , which 30 receive carbon copies of entries made on the top strip a , when detached are designed for use for auditing and accounting purposes and for making records which it is desired to keep, there being as many transfer impression strips as may be required for making 35 up the different records and reports.

In Figs. 3, 4 and 5 of the drawings, I have, for the purpose of illustrating the manner of utilizing the underlying strips containing transfer impressions of entries 40 made on the coupons forming the top strip, shown three different forms of record sheets, designated as a whole, respectively, B, C and D.

As shown, the record sheet B, shown in 45 Fig. 3, is assumed to represent the report of the agent at any station to the auditor's office of the railroad of tickets sold at that point; and is ruled both transversely and vertically to form lines and columns adapted 50 to receive desired entries relating to and descriptive of the tickets sold, including the amount of cash collected for each ticket or the equivalent consideration, if any, said columns comprising a column in which one 55 of the carbon copy strips, as the strips a^1 , is designed to be attached. In order to associate the different carbon copy strips a^1 , when detached, with the entries relating thereto, respectively, the top or upper edges 60 of said carbon copy strips are attached on the transverse line which receives the entries made on said record sheet relating to the tickets corresponding to said carbon copy strips, respectively, the lower ends of 65 said strips hanging loose and the upper

strips overlying the lower strips, all as clearly shown in the drawing.

As shown, the record sheet C, shown in Fig. 4, is practically a duplicate of the record sheet B, shown in Fig. 3, and is assumed to form the record of tickets sold, which is kept by the agent, carbon copy strips, as the strips a^2 , detached with the ticket, being attached thereto in the same manner as the carbon copy strips a^1 are attached to the record sheet B. 70 75

As shown, the record sheet D, shown in Fig. 5, is assumed to represent what is commonly known as an auditing office folio page. The third carbon copy strip a^3 is designed to be pasted or otherwise attached to said sheet D, the carbon copies of entries on different ticket coupons being arranged consecutively according to the numbering of the coupons to which they correspond, thus forming a complete record of all tickets sold. 80 85

I claim:

1. A universal railway ticket form consisting of an indefinite series of coupons of 90 the same size all containing facsimile printed blank ticket forms and provided with corresponding blank spaces adapted to receive appropriate entries, said coupons being detachable singly or in series and all of 95 said coupons to be numbered consecutively whether detached singly or in series, substantially as described.

2. A universal railway ticket form consisting of an indefinite series of coupons of 100 the same size all containing facsimile printed blank ticket forms and provided with corresponding blank spaces adapted to receive appropriate entries, said coupons being detachable singly or in series and all of 105 said coupons to be numbered consecutively from top to bottom whether detached singly or in series, substantially as described.

3. A universal railway ticket form comprising a top strip adapted to receive original entries, an underlying strip or strips, and interposed transfer paper, said top strip consisting of an indefinite series of coupons of the same size all containing facsimile printed blank ticket forms and provided 110 with corresponding blank spaces adapted to receive appropriate entries, transfer impressions of which are reproduced on said underlying strip or strips, said coupons being detachable singly or in series and all of 115 said coupons to be numbered consecutively whether detached singly or in series to form the ticket proper and the registering length of said underlying strip or strips containing transfer impressions of entries on said coupons, being detachable therewith for use in 120 making up records of tickets issued, substantially as described.

4. A universal railway ticket form consisting of an indefinite series of coupons of 130

the same size all containing facsimile printed blank ticket forms and provided with corresponding blank spaces adapted to receive appropriate entries, said coupons being detachable singly or in series and all of said coupons to be numbered consecutively whether detached singly or in series, and each of said coupons to have applied thereto a character to identify the person who issued 10 said ticket, substantially as described.

5. A universal railway ticket form comprising a top strip adapted to receive original entries, an underlying strip or strips, and interposed transfer paper, said top strip 15 consisting of an indefinite series of coupons of the same size all containing facsimile printed blank ticket forms and provided with corresponding blank spaces adapted to receive appropriate entries, transfer impres-

sions of which are reproduced on said underlying strip or strips, said coupons being detachable singly or in series, and all of said coupons to be numbered consecutively whether detached singly or in series and each of said coupons to have applied thereto 20 a character to identify the person who issued said ticket, the strip which receives the original entries forming the ticket proper and the registering lengths of said underlying strip or strips containing transfer impressions of entries on said coupons, being detachable therewith for use in making up records of tickets issued, substantially as described.
